CLAIM

The ornamental design for a display screen or portion thereof with graphical user interface, as shown and described.

DESCRIPTION

FIG. 1 is a first embodiment of a front view of display screen or portion thereof with graphical user interface showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof;

FIG. 12 is a front view of a twelfth embodiment thereof;

FIG. 13 is a front view of a thirteenth embodiment thereof;

FIG. 14 is a front view of a fourteenth embodiment thereof;

FIG. 15 is a front view of a fifteenth embodiment thereof; and,

FIG. 16 is a front view of a sixteenth embodiment thereof. The long dash, short dash broken lines in the figures depict a display screen or portion thereof and form no part of the claimed design. The remaining short dash, short dash broken lines depict graphical user interface and form no part of the claimed design.

1 Claim, 9 Drawing Sheets
